UNITED STATES PATENT OFFICE

ALOYSIUS B. WOBBE, OF SPRINGFIELD, OHIO

GARMENT HANGER

Application filed May 9, 1929. Serial No. 361,801.

This invention relates to garment hangers of that class adapted primarily for use by tailors, dry cleaners and garment pressers, and one feature of the invention is the provision of means, in connection with the ordinary garment hanger, for clamping certain garments to the hanger, whereby the hanger may be transported from place to place without disturbing the position of the garments.

10 A further feature of the invention is in so constructing and arranging the clamping member that it may be attached to the ordinary or any preferred make of garment hanger.

15 A further feature of the invention is in so constructing the clamping member that it will reinforce parts of the ordinary garment hanger and act as a shaper for the garments thereon.

20 A further feature of the invention is the provision of means for attaching an element to the clamping member on which advertising matter may be placed.

A further feature of the invention is the provision of means in connection with the clamping member whereby another hanger or a garment may be suspended therefrom.

Other objects and advantages will be hereinafter more fully set forth and pointed out 30 in the accompanying specification.

In the accompanying drawings which are made a part of this application.

Figure 1 is a front elevation of the preferred form of garment hanger.

35 Figure 2 is an end elevation thereof.

Figure 3 is a front elevation of a modified form of garment hanger.

Figure 4 is an end elevation thereof.

Figure 5 is a front elevation of a further modified form of hanger.

Figure 6 is a sectional view thereof near the line 6-6, Fig. 5.

Referring to the drawings in which similar reference numerals designate corresponding parts throughout the several views, the numeral 1 designates the garment hanger proper, in this instance shown as constructed of wire shaped to form a coat and vest receiving frame 2 and a trousers receiving cross bar 3, the free ends of the

wire being twisted or otherwise secured together and bent to form a hook 4, by means of which the hanger may be suspended from some suitable support.

With the ordinary garment supporter, it has been found that in handling the same after the garments have been placed thereon, that the trousers often shift their position on the cross bar 3 and become crumpled and show various creases which render them unsightly when worn, and to overcome this objectionable feature, a clamping member 5 is provided, which in this instance is attached to the frame 2 by extending the looped ends 6 thereof around the frame 2 on opposite sides of the hook 4. To prevent the clamping member 5 from moving laterally on the frame 2, the bars of the frame are preferably provided with kinked portions 7, with which the looped portions 6 engage.

The clamping member 5 extends downwardly from its point of connection with the frame 2 and is preferably curved to form a shaper for the garment hanging thereover, the extreme lower portion of the clamping member being bent at substantially right angles to form a clamping foot 8 adapted to fit over the cross bar 3 and the trousers hanging thereon, the length of the clamping member being preferably slightly greater than the distance between the hook containing portion of the frame 2 and the cross bar 3, so that it will be necessary to slightly spring the bar 3 downwardly in passing the clamping foot 8 over the bar and garment thereon. The horizontal arms of the foot 8 are preferably upwardly bowed and this bowed portion extends over the cross bar and garment thereon and prevents casual disengagement of the foot from the bar, the extreme forward ends of the horizontal arms of the foot 8 being preferably bent upwardly to form a finger 9, on which another garment hanger or a garment may be suspended.

A plate 10 may be attached to the clamping member 5, in any suitable manner, as by bending tongues 11, formed at the edges of the plate, around the contiguous parts of the clamping member, said plate preventing the

garment entering between the parts of the clamping member and also providing a space for any suitable advertising matter as well as adding rigidity to the clamping member.

5 In that form of device shown in Figs. 3 and 4, the paralleling arms of the clamping member 5 extend substantially in a straight line, instead of being bowed, as shown in Fig. 2, and said arms are shown in closer proximity to each other, but may be separated to provide convenient advertising space therebetween, the other elements and operation of this form being the same as that shown in Fig. 1.

10 15 As shown in Figs. 3 and 4, the cross bar 3 may be provided with a handle member 12, so that the bar may be more readily sprung downwardly to permit the foot 8 to be engaged therewith or disengaged therefrom.

20 25 In Figs. 5 and 6, the hanger frame proper 13 is constructed in the conventional manner of wood, with a wood cross bar 14, the clamping member 5 being attached to the under side of the frame 13 in any suitable manner, as by means of staples 15, or screw eyes (not shown) or other convenient means.

30 35 In applying this device to use, a pair of trousers or other garment is first arranged over the cross bar of any form of hanger used and by directing a slight rearward push against the clamping member, the foot portion 8 thereof will readily pass over the cross bar and garment thereon and clamp the same in position on the cross bar, so that the

40 45 hanger may be shifted from place to place or transported without disarranging or crumpling the garment suspended on the cross bar. A coat or other similar article of wearing apparel, or a coat and vest is then placed over the frame of the hanger in the usual manner, when the hanger may be suspended by the hook 4 from any convenient support.

50 55 In the event of limited space in which to suspend the hangers, an additional hanger may be suspended from the first hanger by engaging the hook 4 of the second hanger with the finger 9 of the first hanger, then a third hanger to the finger of the second hanger, and so on until the requisite number of hangers have been suspended.

60 65 In removing the trousers or other garment from the cross bar, the clamping member is forced forwardly by giving the same a slight forward push, until the foot 8 is released from the cross bar and garment thereon, when the garment may be removed from the cross bar. As the clamping member is hinged to the frame of the hanger, it will readily swing forward, when released from the cross bar, so that it will not interfere with the placing of the garment over the cross bar or removing the same therefrom.

70 75 What I claim is:

80 85 1. A garment hanger comprising a frame, yielding cross bar at the lower extremity

thereof, a clamping member pivotally attached at its upper end to the upper portion of said frame, a foot formed by bending the lower extremity of said clamping member substantially at right angles, and upwardly bowed portions incorporated with said foot 70 adapted to be forced over said cross bar and clamp an article thereon.

2. A garment hanger comprising a frame, a cross bar at the lower extremity of said frame, a clamping member pivoted at its upper end to the upper portion of said frame and bowed outwardly from its upper to its lower end for shaping parts of a garment extending thereover, and a foot formed by bending the lower extremity of the clamping member 75 at right angles to the remaining portion thereof.

3. In a garment hanger, a frame, a cross bar at the lower extremity thereof, a clamping member pivoted to said frame and of a length slightly greater than the distance between the pivot point of said clamping member and the cross bar, and a foot portion at the lower extremity of said clamping member 80 adapted to be forced over said cross bar by springing said bar downwardly, said foot portion having upwardly bowed portions 85 forming a seat for said cross bar and preventing casual swinging movement of the 90 clamping member.

95 In testimony whereof, I have hereunto set my hand on this the 13 day of April, 1929, A. D.

ALOYSIUS B. WOBBE.
